INVENTOR.
Isadore Leiker,

BY:

Geo. P. Kimmel. ATTORNEY.

UNITED STATES PATENT OFFICE.

ISADORE LEIKER, OF HAYS, KANSAS.

SLOT CLOSURE FOR FORD AUTOMOBILES.

Application filed February 2, 1923. Serial No. 616,568.

To all whom it may concern:

Be it known that I, ISADORE LEIKER, a citizen of the United States, residing at Hays, in the county of Ellis and State of Kansas, have invented certain new and useful Improvements in Slot Closures for Ford Automobiles, of which the following is a specification.

This invention relates to slot closures for 10 Ford automobiles, and its object is to provide a means to prevent a cold draught in the winter time and shut off the hot air from the engine in the summer time.

The invention comprises a set of slide 15 members each with a slotted guard plate individual thereto through which the brake lever slide or guard plate, the clutch lever slide or guard plate, and the reverse lever slide or guard plate pass and control.

20 The construction is such that the guards may be removed at any time or applied at any time to effectively protect the operator from the hot air or from the draught to which the operator is subjected.

25 The invention will be best understood from a consideration of the following detailed description taken in connection with the accompanying drawings forming part of this specification, with the understanding 30 that the invention is not confined to any strict conformity with the showing of the drawings, but may be changed and modified so long as such changes and modifications mark no material departure from the salient 35 features of the invention as expressed in the appended claims.

In the drawings:—

Figure 1 is a longitudinal vertical section through one of the control lever protecting 40 plates but omitting the other control levers from consideration.

Fig. 2 is a perspective view of the guard plate for the control lever illustrated.

Fig. 3 is a perspective view of the associated stationary guard plates directly controlled by and movable with the foot lever.

Referring to the drawings, there is shown in Fig. 2, the driver's compartment A of a Ford automobile and showing but one of the 50 control foot levers 1 of the complete equipment, the other levers being omitted as substantial duplicates of the particular lever illustrated and hence not necessary to show, it being understood that in practice two 55 other foot levers are assumed to be present,

the three levers making up the complement of three foot levers usually present in the Ford automobile for controlling the high speed and the low speed clutch, the reverse control and the brake control but it is considered unnecessary to show all three of the levers as in general their structure is similar.

To accommodate the three levers, there are provided three longitudinal slots 2 to 60 pass the several foot levers constituting the control of the automobile, although but one of these foot levers, namely the foot lever 1 is illustrated in the drawings, because the other two levers are effectively duplicates 65 of the one shown.

Each foot lever 1 is mounted on a shaft 3 below the slanting floor board 4 which passes all three of the foot levers, and each foot lever terminates at the upper end 75 above the floor board or deck 4 in a foot pedal 5 common to the Ford automobile.

On the upper face of the deck 4 and secured thereto by bolts 6, or other suitable fastening devices, is a fixed plate 7 having 80 a central longitudinal entering slot 17 and longitudinal side slots 9 to accommodate the fastening bolts 6 for the adjustment or locating of the plates 7.

The foot lever 1 extends normally at a 85 rising inclination through the slot 2 and above the top of the deck 4 and traverses it, and this lever 1 rises through and is secured to a guard yoke 8 embracing the lever 1 above the slot 2, the guard yoke 8 90 being secured to the lever by means of a clip 8' extending through a slot 10 in the yoke 8 embracing the lever 1 and made fast thereto by a bolt 11 extending about the rear of the lever 5 so that the shield 8 will 95 participate in movements of the lever under the control of the foot of the operator.

The guard yoke 8 has a pivot connection 12 with one end of the guard plate 13, while the other end of the guard plate 13 is formed 100 with a downturned extension or flange 14 to slide along the under face of the deck 4 without interference therewith.

The guard yoke 8 is connected by an extension spring 15 with an intermediate hook 105 or connection 16 on the guard plate 13 and tending to hold the foot lever 1 in a relatively elevated position.

When pressure is exerted by the foot of the operator upon the pedal 5, the plate 13 110

is moved about the pivot 12 with the guard yoke 8 participating in such movement and extending the spring 15 so that the spring 15 is caused to move through a longitudinal slot 17 at the end of the plate 7 remote from the slot 17 thus extending the spring 15 and permitting the movement of the plate 7 below the lower edge of the deck 4, the guard yoke 8 and spring 15 moving below the deck 4, still effectively closing the slot in the plate 7 against any material passage of air, hot or cold, through the plate 13.

In assembling the structure with respect to the deck of the Ford automobile, the plate 7 is located above the deck and made fast thereto by the bolt 6 or other suitable means with a plate 18 located below the deck 4 and constituting a thick closure for the bottom portion of the deck.

20 The plate 13 is located below the deck 4 and underneath the slots 9 and 17 and permitting the raising and dropping of the plate 13 together with the lever 1, this structure being duplicated with respect to each 25 of the other foot levers.

Ordinarily, the plate 13 is in the raised condition with the flanged end 14 against and slidable along the under side of the face of the deck 4, while the other or rear 30 edge of the plate 13, this being the hinged end 12, rises and falls with respect to the under face of the deck under the pressure of the foot of the operator in working the control levers of the automobile, the guard 35 yoke 8 participating in this movement, each control lever causing the operation of the part participating in the movement of the respective control lever through the shaft 3.

With the parts assembled, the slots 40 through the deck 4 are only temporarily open, and the effects of draught therethrough are but temporarily felt and not sufficiently to chill the operator in winter time or to expose the operator to the effects 45 of the hot draught coming from the engine in the summer time.

What is claimed is:—

1. A closure for the pedal slot in the control mechanism of a Ford automobile, comprising a plate fixed to the upper face of the deck of the automobile, and another plate slidable along the under face of said deck and hinged to a control pedal to move therewith and participate in the approach and recession of the pedal with respect to 55 said deck.

2. A closure for the pedal slots of the control-lever-mechanism of a Ford automobile, comprising a longitudinally slotted plate with fastening means for adjustably fixing it to the upper face of the deck of the automobile, and another plate provided with a sliding connection to said deck and having a hinged member for attachment to a pedal lever of the control mechanism, whereby the pedal has a hinged connection participating in the movements of the pedal to and from the deck and serving as a means for preventing draught openings through 60 said deck.

3. In a draught closure for the control lever system of a Ford automobile, a plate for the deck of the automobile fixed thereto, and another plate movable bodily toward and from the under face of the deck and having a hinge connection with one of the control pedals to move therewith.

4. In a draught closure for the control lever systems of a Ford automobile, a deck closure plate of the automobile, a second deck closure plate having one end provided with a stop lip and the other end provided with a hinged connection to the opposite end of the second plate, and a yoke to encircle and be made fast to one of the foot pedals of the control pedal system and having a spring connection with the second closure plate and entering a longitudinal slot in the first closure plate.

In testimony whereof, I affix my signature hereto.

ISADORE LEIKER,
